MECHANISMS FOR FEEDING DISK-TYPE CAPACITORS AND LIKE ARTICLES

Albert E. Newton, Beverly, Mass., assignor to United Shoe Machinery Corporation, Flemington, N.J., a corporation of New Jersey

Application February 25, 1957, Serial No. 642,281

5 Claims. (Cl. 214—8)

This invention relates to mechanism for feeding and orienting articles, and more especially to the provision of improved means for feeding and controlling round articles, such as certain electrical components which must be uniformly positioned in order thereafter to be dealt with in a precise and proper manner. The invention is herein illustrated as embodied in hopper mechanism for handling disk-type capacitors and thus, in one aspect, concerns the provision of improvements in feed mechanism of the type disclosed in a copending application Serial No. 525,330, filed July 29, 1955, in the name of Milton H. Roske (now Patent No. 2,855,113, granted October 7, 1958). It is to be noted, however, that the present invention is not limited in use to any particular type or shape of work piece and, indeed, in some aspects the invention is not necessarily restricted to feeding means of the illustrative type.

Assembling, packaging, and other types of machines for processing articles frequently require them to be successively isolated from a random mass and then individually fed and/or positioned in a predetermined manner. This treatment often involves nice mechanical considerations, especially if the articles being fed are of irregular configuration. The above-mentioned application discloses, for example, a feeding mechanism comprising the combination of a rotary plate formed to segregate disk-type capacitors and successively position them in the course of its rotation, and means for transferring the positioned capacitors for uniform stacking in a receptacle. Although this feeding mechanism is highly useful in facilitating an adequate supply and orderly arrangement of the work pieces and has proved itself of considerable value when used in conjunction with inserting machinery, the feeding performance is in some respects not entirely satisfactory and certain of its limitations in feeding disk capacitors, for instance, may be mentioned. Upon being segregated by the specially formed capacitor positioning plate, each successive component is transferred by the respective pick-off nozzles of a wheel to be deposited in the mouth of a tube or delivery chute. A guide rod extending longitudinally in the chute is provided to be straddled by the pairs of radially extending leads of the components and thus maintains their stack formation and guides them for delivery. Aside from the fact that the bodies of the components are usually lacking in exact uniformity of contour, thus frequently preventing precisely similar positioning at the point of pick-off, it often happens that the leads of the components are neither parallel, straight, or radial, but are irregularly bent and thus, when a component has been placed in the chute and on the guide rod, its leads may not be well aligned with other leads in the stack even though its body is so aligned with other bodies. Moreover, although the formation and operation of the rotary segregating plate may be such as uniformly to position work pieces at the pick-off point, it is frequently found that the pick-off wheel or other presently known transfer devices cannot remove the

2

work pieces and deliver them into a receptacle with exactly the desired degree of change in their orientation which may be needed thereafter to feed them by gravity to a point of utilization. Lastly, continued operation of the pick-off wheel, when the chute is fully loaded with components, is undesirable from the standpoint of efficiency and also perhaps because unnecessary tumbling of the work pieces may be detrimental to their condition.

In the light of the foregoing, a particular object of 10 the present invention is to provide certain improvements and added versatility in the Roske feeding mechanism whereby it is made more efficient and delivers work pieces in more nearly uniform position and condition. Considered more generally, it is a primary object of this 15 invention to provide improved means for delivering regularly and/or irregularly shaped articles from a random mass into an orderly oriented stack.

With these objects in view, one feature of the invention resides in the provision of novel feeding mechanism 20 having, in combination with a rotary plate formed to position successive components from a mass and a receptacle for receiving these components in uniform formation, transfer means mounted for cooperation with the plate, the transfer means being constructed and arranged to remove the successive components from their 25 position determined by the plate and turn them a selected number of degrees for deposit in substantial alignment on a guide rail in the receptacle. As herein disclosed, this transfer means consists of a rotary wheel having circumferentially spaced suction nozzles disposed to "pick off" the components positioned by the plate, and cam means cooperative with the respective nozzles is arranged to turn them the desired amount in one direction during transfer of the components, the nozzles being restored 30 to pick off position after being relieved of their work pieces. Preferably, the component turning effected during transfer is sufficient to insure that the median plane between the leads of a component will substantially coincide after rotation with a median plane extending 35 through the guide rail.

Another feature of the invention, one by no means limited to the illustrative embodiment or even to component feeding mechanism generally, is the provision of novel means for insuring that the pairs of leads of a 40 plurality of components being fed will be spread apart by a minimum spacing, said means comprising a receptacle formed with a passageway confining the bodies of the components in stacked formation, a guide extending longitudinally in said passageway between the leads of each pair and adapted to engage corresponding ones of 45 said leads to hold them and their bodies against rotation in one direction about an axis, and a member movably mounted in said guide for engagement with the corresponding other ones of said leads to cam them in said 50 one direction and away from the first-mentioned leads. As herein shown, the lead spreading member is arranged to be mechanically oscillated and its periphery is relieved to provide a non-lead engaging surface such that little or 55 no interference with progressive feeding is experienced.

60 The above and other features of the invention, including means for automatically stopping operation of the transfer means upon loading of the receptacle, and other novel details of construction, will now be more fully described in connection with an illustrative embodiment 65 and with reference to the accompanying drawings thereof, in which—

Fig. 1 is a perspective view of the improved feeding means as adapted for dealing with disk-type capacitors, control means being diagrammatically indicated;

70 Fig. 2 is an enlarged view, with portions broken away, of a rotary segregating plate, a transfer wheel and chute

largely shown in Fig. 1 and looking in a direction normal to the plate;

Fig. 3 is a view, partly in section, of parts shown in Figs. 1 and 2, as seen when looking at the transfer wheel in a direction normal to the operating plane of the plate;

Fig. 4 is a section taken on the line IV—IV of Fig. 2 and illustrating the successive positions of a disk capacitor and means for turning it with its carrying nozzle;

Fig. 5 is a view largely in vertical section of the chute shown in Fig. 1, as seen when looking in the direction of the arrow in Fig. 6, and showing means by which a minimal spread of leads is insured;

Fig. 6 is a plan view of the parts shown in Fig. 5, and indicating introduction of a component into the chute and onto its guide rod;

Fig. 7 is an enlarged section taken on the line VII—VII of Fig. 5, and showing the lead spreading means in inoperative position; and

Fig. 8 is a further enlarged view corresponding to Fig. 7, but showing the lead spreading means in operative position.

Since the illustrative feeding means is intended to deal with disk-type capacitors C having leads L, it will be noted that a rotary segregating plate 10 (Figs. 1, 2 and 3) has a circular configuration especially adapted therefor and substantially like that shown in the Roske application referred to above. It will be appreciated that segregating and positioning means of other configuration may be employed for discaps and other work pieces without departing from the scope of this invention. The plate 10 is inclined and constitutes the bottom of at least the portion of a hopper 12 in which the discaps to be successively fed in orderly arrangement are maintained in random fashion. As the plate 10 is rotated clockwise about its center, as seen in Fig. 1, by means of a driven cross shaft 14 and a helical gear 16 fixed thereon, arcuate edges of successive work receiving recesses 18 formed in the plate usually lift one or more discaps C, each one of these retained in its recesses being slidably and revolvably supported until it is positioned substantially as shown in the upper right portion of Fig. 1. Means including ejector pins 20, 20 are automatically actuated to return improperly positioned components to the hopper 12, each correctly positioned component being allowed to proceed to a pick off point depicted in Figs. 2 and 3, which is located preferably on or near a level with the center of the plate 10 and substantially in tangential relation to the path of four work holders preferably in the form of rubber pick off nozzles 22 mounted on and extending radially from a pick off wheel generally designated 24.

For driving the wheel 24 clockwise, as viewed in Fig. 1, and in proper time relation with the plate 10, i.e., so that successive nozzles 22 may transfer from the pick off point the components successively arriving in their respective recesses 18, the cross shaft 14 drives a gear 26 (Fig. 1) mounted thereon. The latter is in mesh with an intermediate gear 28 that has bearings in a bracket 30 supported by the hopper 12, the gear 28 in return driving a pinion gear 32. The wheel 24 is mounted on an axially bored hub 34 that is fixedly supported in the bracket 30 and supports the gear 32. A rotor 38 on the hub is driven by the gear 32 and formed at one end with four equally spaced radial bores 40 (one shown in Fig. 3), each of which is threaded rotatably to receive an adaptor 42 carrying one of the nozzles 22. To enable each successive nozzle to pick up a capacitor as properly positioned in its recess at the pick off point, one end of the bore of the hub 34 is in communication with a source of reduced pressure by means of a tube 44 (Fig. 1), and the other end of the bore connects with a radial aperture 46 (Fig. 3) in the hub. This aperture is of a size and position to enable each bore 40, while traversing the aperture, to cause the positioned component body to be transferred from its recess and pressurally held against the outer end

of the nozzle 22 until the latter is over the mouth of a vertical chute generally designated 48, suction through the bore 40 then being effectively terminated to release the component for a fall into the chute. As thus far described, the structure is largely as disclosed in the application above cited.

In order better to insure that each component positioned by the plate 10 can thereafter be received on and properly oriented by a guide rail 50 (Figs. 2, 3) into selected position in stack formation in the chute 48, means is provided for turning each adaptor 42, together with its nozzle, about their axis in the course of transfer of the component. For this purpose, the normal or "pick off" position of each adapter is determined by a pin 52 (Figs. 1, 2 and 3) fixed therein that is yieldingly held in engagement with an adjustable stop arm 54 projecting from the rotor 38, said pin being acted on by means of a spring 56 (Fig. 1). The latter is anchored at one end to a pin 58 extending radially from the rotor and at its other end to the adaptor pin 52. A radially depending portion of the hub 34 serves as a fixed cam 60 (Figs. 2 to 4) arranged to be engaged by an angular finger 62 projecting from each adaptor. Accordingly, as a component is being transferred to the chute, the component, together with its carrying nozzle and adaptor, are caused to be rotated the desired number of degrees and against the resistance of the spring 56 as the finger 62 engages and moves over the surface of the cam 60, successive stages in the orienting action being shown in Fig. 4. The shape of the operating surface of the cam 60 is such as to cause the leads L of a component being transferred to be turned adequately to insure their straddling the upper end of the rail 50, as shown in Fig. 2. Ideally this means that the median plane extending between straight leads of a typical component being fed will be shifted to coincide with, or substantially coincide with, the apex of the tapered end of the rail 50. By way of distinguishing further over the prior construction, it is to be noted that the upper portion of the guide rail 50 extends helically, its upper end being disposed in the path of the component bodies for contact therewith. The rail 50 thus serves as a wipe-off or positive releasing tool for correcting any non-uniformity in the point of terminating suction on the components.

As herein shown, a portion 64 (Figs. 1 and 5), integral with the hopper 12, supports, for adjustment about a vertical axis, a cylindrical tubular member 66 having a spirally formed inner surface from which the helical rail 50 internally projects, the member 66 having a funnel-shaped passageway 68 (Figs. 5 and 6) for the nozzles which is arranged to guide the leads onto the rail. For control purposes later described, the member 66 also serves to support a photo-electric cell 70 (Fig. 1) and a light source 72, and is accordingly formed with aligned slits 74 which allow a light beam to pass between the cell and the member when no component is stored between the slits. Secured to the portion 64 is a block 76 for mounting a lower tubular portion 78 of the chute 48. A vertical rail 80 (Figs. 1, 5, 7 and 8) of rectangular section is adjustably secured by a block 82 mounted on the block 76 so that the rail 80 extends longitudinally of a height-wise slot in the portions 78 and 64, and is a continuation of the helical rail 50. After a component is delivered by the nozzle 22 to the rail 50 so that the latter is straddled by the pair of leads, the component falls in horizontal position, preferably not more than about an inch, onto an aligned stack of previously fed components in the tubular portion 78, the leads moving into engagement with, or nearly into engagement with, the oppositely disposed vertical sides of the rail 80. In order to insure that the leads of the components in the stack will have a minimum spread, for example to improve their conformity with the spacing of lead-receiving holes preformed in a printed wiring board, and also to avoiding binding or cramping of the leads on the rail, a spreader 83 (Figs. 1, 5, 7 and 8), preferably in the form of an oscillatory cam, is provided.

Operation of the spreader constitutes, in effect, a dynamic means by which the width of a portion of the rail is apparently modified one or more times as the leads pass thereby. The spreader shown has a conical top and is largely recessed in a cylindrical bearing bored in this instance in the upper end of the guide rail 80. The lead-engaging surface of a spreader need not be cylindrical but may be otherwise shaped and disposed to engage either one or both of the leads of a component. In its inoperative position (Fig. 7) a slabbed-off side 84 of the spreader is substantially level with a side of the rail 80, but when oscillated about a vertical axis by means to be explained, the lead-engaging surface of the spreader projects from one side of the rail in the manner illustrated in Fig. 8. Accordingly, after a component is thus turned about a vertical axis until one of its leads abuts a side of the rail 80, the spreader further acts on the other of its leads repeatedly to urge it outwardly and cause it to assume a spread position. Repetitive outward dilating or bending to overcome lead resilience is thus exerted simultaneously on the corresponding leads of each of several components as they progress downwardly.

For oscillating the spreader 83 about a vertical axis, a forked arm 86 (Fig. 1) thereof is connected by a link 88 to one end of a rod 90 slidably mounted in the portion 64. The rod 90 is reciprocated by means of pin and slot connection with an arm of a bell-crank lever 92 pivotally supported on a pin 94 secured in the hopper portion 64, another arm of the bell-crank lever being actuated by a link 96 driven from a lug 98 projecting from the gear 26.

In the Roske disclosure mentioned, means in the form of an intermittent air blast is used to return excess components from the mouth of the loaded receptacle to the hopper 12 to await another positioning by the plate 10. Components thus excessively tumbled may become unnecessarily worn, and occasionally indicia printed on their bodies may become unreadable. Accordingly, as indicated diagrammatically in Fig. 1, means is provided for automatically discontinuing the pick-off operation of the transfer wheel 24 as soon as the chute 48 is substantially full of components, a component in the chute then interrupting passage of a light beam through the slits 74 and consequently deenergizing a circuit connected through a master switch 100 (Fig. 1) to a solenoid valve 102. As a result, the latter is actuated to discontinue the reduced pressure in the line 44 until, depending on the rate of use of the components and assuming a normal delivery rate from the plate 10, the stack in the chute falls to a maximum level beneath the slits of about the combined thickness of four or five component bodies.

Operation of the feeding mechanism will readily be understood from the foregoing description. A preliminary step normally required before actuating the switch 100 to commence automatic feeding is the loading of chute 48 with components preferably up to a point only a few components' thickness beneath the slits 74 thus insuring that components deposited by the nozzles 22 will not become wedged or skewed before assuming horizontal stacked relation. Turning the nozzles 22, or other suitable work holders which may be substituted therefor, to the desired degree during transfer of the disk capacitors or other work pieces enables the segregating mechanism to be more effective in causing leads to straddle the guide rails which may be turned at different angles about a vertical axis. The lead spreading action enhances uni-

formity in the relative positions of the leads and incidentally serves a dithering function to insure continuous flow of components by gravity in the chute.

Having thus described my invention, what I claim as new and desire to secure by Letters Patent of the United States is:

1. Article feeding mechanism comprising means movable to segregate articles from a random mass and position them successively at a transfer point, a chute having a longitudinally extending rail adapted to guide articles in stacked formation therein, and transfer means constructed and arranged for movement in time relation to said segregating means to carry the successive articles from said point for deposit in said chute, said transfer means including at least one holder rotatable in a fixed path and about its own axis to enable the articles when released to straddle said rail.
2. Mechanism as set forth in claim 1 and further characterized in that said transfer means is mounted on a hopper and mechanism mounted on said hopper is disposed yieldingly to turn the holder axially a predetermined number of degrees after it has passed said transfer point and before depositing its articles.
3. In mechanism for feeding components having spaced leads, a guide rail adapted to be straddled by the respective pairs of leads of a plurality of components advancing longitudinally of the rail, a lead spreading member mounted in the rail and having an effective movement transversely thereof, and mechanism for operating said member to cause its lead-engaging surface to extend beyond at least one side of the rail and against the leads adjacent to said side whereby said pairs of leads are provided with a substantially uniform minimal spread.
4. In mechanism for feeding components respectively having a pair of leads projecting from their bodies, a rail adapted to be straddled by the respective pairs of leads of a plurality of components while guiding the components in row formation, a member dynamically associated with the rail and having a lead-engaging surface arranged to be moved transversely of the rail to deflect the end portions of the leads a uniform extent from the end portions of the other leads of the respective pairs, and means for repeatedly operating the member to overcome resilience of the leads to such deflection, to cause the spread of the lead end portions to be substantially equal.
5. Mechanism as set forth in claim 4 and further characterized in that said member consists of a cylindrical spreader member mounted for rotation about an axis in a recess in said rail, said member having a cylindrical lead engaging surface arranged to project from the rail to dilate the pairs of leads and having a slabbed-off surface substantially parallel with said axis and disposed to avoid engagement with the leads.
